VAPOR ELECTRIC CONVERTER

Hans Klemperer, Pittsburgh, Pa., assignor to
Westinghouse Electric & Manufacturing Company,
East Pittsburgh, Pa., a corporation of
Pennsylvania

Application January 13, 1938, Serial No. 184,835

6 Claims. (Cl. 175—363)

My invention relates to a vapor electric converter, and more particularly to an excitation system for such converter of the high-voltage type.

5 In the operation of vapor electric converters, particularly of the high-voltage type, comprising an anode, a mercury pool cathode and an igniter electrode in permanent contact with the cathode, the excitation arc is frequently advanced in phase 10 with respect to the main arc in order to keep ionization low during the latter part of the conducting period. It frequently happens during the latter part of the conducting half cycle that the cathode spot formed at the igniter rod- 15 mercury junction jumps to an auxiliary anode provided with such devices. This movement of the cathode terminal of the main arc occurs because the auxiliary anode is more negative than the cathode during the latter part of the conducting period.

20 Droplets of mercury sputtered during the initiation of the cathode spot often strike the auxiliary anode and the unwanted arc transfer becomes more favorable to the movement of the mercury droplets. However, an adverse effect upon the 25 operating conditions of the discharge device is the natural result and considerable damage is caused to the auxiliary anode as well as the creation of backfire hazards.

30 According to my invention, the position of the grid-controlled discharge device which supplies unidirectional current to the igniter electrode is changed to prohibit the auxiliary anode from becoming more negative than the cathode during 35 the latter part of the conducting period. Immediately at the transition point, that is, the point at which the exciting current reaches zero, the excitation arc is extinguished. The main arc, however, continues to persist because anode current is still flowing. During the interval, that 40 is, between the transition points of the excitation current and the anode current, negative potential does not flow to the auxiliary anode for a unidirectional conductor such as a half-wave rectifier 45 is in the circuit supplying current to both the igniter electrode and the auxiliary electrode. Without the unidirectional conductor in the new position, a high negative voltage would be applied rapidly to the auxiliary anode and a very 50 high initial back current would flow for at least a short interval of time because of the high density of ionized vapor present in the anode region.

It is, therefore, an object of my invention to 55 prevent the transfer of the cathode spot of the

main arc to the auxiliary anode during the latter part of the rectifying period.

Another object of my invention is to accelerate the transfer of the anode side of the auxiliary arc from the igniter rod-mercury-junction to the auxiliary anode of such devices.

Another object of my invention is to provide suitable means for reducing damage to the auxiliary anode of vapor discharge devices and the consequent backfire resulting therefrom.

Other objects and advantages of my invention will be apparent from the following detailed description taken in conjunction with the accompanying drawing, in which:

Figure 1 is a diagrammatic illustration of a 15 vapor electric converter and circuits embodying my invention.

Fig. 2 is an illustration showing an alternative circuit for operating vapor electric converters, and

Fig. 3 is a graphical illustration showing the 20 phase relationship of the working currents according to my invention.

The converter 3 according to Figure 1 of my invention comprises a suitable evacuated container 5 having an anode 7 and a mercury pool 25 cathode 9 disposed in the bottom thereof. The converter 3 supplies unidirectional current to a load device 4 from a source 6 of alternating current. An auxiliary anode 11 is interposed between the main anode 7 and the cathode 9 to 30 control the rectifying arc being maintained in the converter 3. An igniter electrode 13, preferably of some high resistance material, is mounted to be in permanent contact with the cathode 9. The ignition electrode 13 and the auxiliary anode 35 11 are electrically connected at point 14. A unidirectional conductor 15, such as a half wave rectifier, is placed between a source of suitable alternating current potential such as a transformer 17 and the auxiliary electrodes 11 and 13. 40 Between the transformer 17 and the unidirectional conductor 15, a suitable resistor 19 is placed to limit the current supplied to the auxiliary anode 11 which is preferably a thin circular disk of some suitable metal. Likewise, a 45 resistor 21 is placed in series with the igniter electrode 13 to facilitate the arc transfer from the igniter rod-mercury junction to the auxiliary anode 11. According to my invention it is essential to shift the phase of the current supplied to the auxiliary electrodes 11 and 13 with respect to the anode current. I have illustrated a convenient method for producing this phase shift by a suitable phase shifter 23.

According to Fig. 2 of my invention, the only 55

difference lies in the method of supplying exciting current to the auxiliary electrodes 11 and 13. A peaking transformer 25 having a plurality of windings 27 and 29 is used for generating voltages of substantially perpendicular wave fronts. In connection with the peaking transformer 25, I illustrate a desirable type of phase shifter which essentially consists of a plurality of windings 28 and 29 connected to a common source of supply 31 in a reverse direction and a resistor 33 is used to control the excitation current of one of the windings 28. A leakage path 35 is customarily provided between the primary windings 28 and 29, such as is used in connection with the transformer 25 utilizing opposed alternating current windings 28 and 29. By such an arrangement of a highly saturable core 37, grid control of the unidirectional conductor 15 or grid-controlled rectifier is unnecessary.

20 Alternating current is supplied from the transformer 17 and the unidirectional device 15 permits current to flow to the auxiliary electrodes 11 and 13 only during conducting half cycles, that is, when the anode 7 is maintained positive 25 with respect to the cathode 3. To maintain ionization low during the latter part of the conducting half cycles, a suitable means such as a phase shifter 23 for advancing the excitation current ahead of the main anode current is provided. The working currents are graphically 30 illustrated in Fig. 3 where A represents the current supplied to the auxiliary electrodes 11 and 13 and B the current supplied to the main anode 7.

35 The formation of a tiny arc occurs between the igniter electrode-mercury junction when the potential gradient in the igniter rod 13 reaches or exceeds a certain critical value. Potential gradient is established by passing a current to the igniter electrode 13 from some suitable source such as a transformer 17. The lower terminal of this arc, or better known as the cathode spot, moves away from the igniter rod 13 along the surface of the mercury cathode 9. On the other 40 hand, the upper terminal of this arc travels upwards along the igniter electrode 13 with extreme rapidity to the auxiliary anode 11. By selecting a suitable point on the forward half cycle, a discharge will start between the cathode 45 9 and the main anode 7.

Upon reaching the zero or transition point, represented by letter C in Fig. 3, the excitation current ceases to flow and the arc between the cathode 9 and the auxiliary anode 11 is extinguished while the arc between the cathode 9 and the main anode 7 continues to persist until the transition point, represented by letter D, of the main anode current is reached. During this time, that is, between points C and D, the cathode spot is prevented from jumping to the auxiliary anode 11 because the current is blocked during the inverse half cycle by a unidirectional current-transmitting device 15. This is shown as a three-element thermionic discharge tube, 55 but may alternately be any equivalent device capable of passing current only when the mercury pool 9 is at a negative potential with respect to the main anode 7. It may be desirable to accelerate the transfer of the arc between the cathode 9 and the auxiliary anode 11. A suitable resistor 21 is provided for this purpose, so that when current is being supplied to the igniter electrode 13, a voltage drop across the resistor 21 hastens the arc transferring process between 60 the auxiliary electrodes 11 and 13.

Grid control of the thermionic discharge tube 15 may be eliminated by using an inductive device such as a peaking transformer 25 capable of generating voltages having peak wave fronts. By this arrangement, current flows through the unidirectional device 15 only for a short period of time during the conducting half cycle.

For purposes of illustration, I have shown a specific embodiment of my invention. However, it will be apparent to those skilled in the art that changes and modifications can be made therein without departing from the true spirit of my invention and the scope of the appended claims.

I claim as my invention:

1. A vapor electric converter comprising an evacuated container, an anode, a mercury cathode, an auxiliary electrode between said anode and said cathode, an igniter electrode in contact with said cathode, a source of exciting current connected to said auxiliary electrode and said igniter electrode for initiating a cathode spot at the igniter rod-mercury junction, another source of exciting current lagging in phase relationship with respect to said igniter current for maintaining a rectifying arc between said cathode and said anode and a unidirectional device for preventing transfer of the cathode terminal of said arc to said auxiliary electrode at the transition point of said igniter current until said rectifying arc is extinguished.

2. A vapor electric converter comprising an evacuated container, a plurality of main electrodes, an auxiliary electrode disposed between said main electrodes and an igniter electrode in contact with one of said main electrodes, means for establishing and maintaining a rectifying arc in said converter, said arc establishing means including a source of exciting current and means for initiating an auxiliary arc between one of said main electrodes in contact with said igniter electrode and said auxiliary electrode, and means including a unidirectional conductor for preventing the transfer of the cathode terminal of said rectifying arc to said auxiliary electrode after said auxiliary arc is extinguished.

3. A vapor electric converter comprising an evacuated container, an anode, a cathode, an auxiliary electrode between said anode and said cathode and a make-alive electrode in contact with said cathode, an electrical connection between said auxiliary electrode and said make-alive electrode, a common source of exciting current for said electrically connected electrodes and a unidirectional conductor between said current source and said connected electrodes whereby said auxiliary electrode is prohibited from becoming more negative than said cathode.

4. A vapor electric converter comprising an evacuated container, an anode, a vaporizable cathode, an igniter electrode in contact with said cathode and an auxiliary electrode disposed above said cathode, said auxiliary electrode and said igniter electrode being electrically connected, a source of exciting current, a unidirectional device between said current source and the terminal point of said joined electrodes and a resistor between said igniter and said terminal point whereby an arc initiated at the igniter-cathode junction is accelerated to said auxiliary electrode upon passage of current to said igniter electrode.

5. In combination with a vapor electric converter comprising a plurality of main electrodes, an igniter electrode in contact with one of said main electrodes and an auxiliary electrode between said main electrodes, a source of exciting

5 current for initiating a cathode spot at the junction of said igniter and one of said main electrodes in contact therewith, another source of current for maintaining a rectifying arc between said main electrodes, means for displacing said 10 current sources in phase relationship, said dephasing means including a peaking transformer for generating impulses of steep wave fronts and a unidirectional device in series with said trans-
15 former whereby the alternate impulses are impressed on said igniter and said auxiliary electrode, said unidirectional device serving to prevent the cathode terminal of said rectifying arc from transferring to said auxiliary electrode at the transition point of said igniter current.

6. In combination with a vapor electric con-

5 verter comprising a plurality of main electrodes, an igniter electrode in contact with one of said main electrodes and an auxiliary electrode between said main electrodes, said igniter electrode and said auxiliary electrode being electrically connected, means for applying positive potential to said igniter electrode before application of like potential to one of said main electrodes, said supply means for said igniter electrode including a peaking transformer for generation of impulses 10 having steep wave fronts, and means connected in series with said electrically joined electrodes for rendering said joined electrodes inoperative during inverse potential.

HANS KLEMPERER. 15
